FUEL SUPPLY SYSTEM

Frederick Ritz, Hamilton, Ohio, assignor to Fairbanks, Morse & Co., Chicago, Ill., a corporation of Illinois

Application March 9, 1936, Serial No. 67,879

8 Claims. (Cl. 123—139)

This invention relates to improvements in fuel supply systems for internal combustion engines, and more particularly to an improved, self-priming fuel supply system having particular application to liquid-fuel injection engines of Diesel type, or the like.

An object of the present invention is attained in the provision of an improved positive-pressure fuel supply system for engines of the type noted, 10 in which the elements forming the system are advantageously disposed in a closed-circulation arrangement which is automatic and efficient to an improved degree in its purpose to supply fuel to the injection pumps of Diesel engines and the like, and further, to provide a fuel supply system which is self-priming.

Another object is to be found in the provision of an improved fuel supply system of closed-circulation type, in which certain of the elements included in the system are so operatively related as to tend to prevent a backflow of fuel in the system, and further, in the provision of means associated with the organization of the engine fuel injection pump, for utilizing the 20 ejector and pressure wave action of the excess fuel expelled or released by the pump, in maintaining a continuous unidirectional circulation of fuel in the closed-circulation system.

A further object may be found in the provision, in combination with an inverted fuel pump, of an improved fuel supply system for engines of the type described, characterized by a positive pressure, continuously circulated fuel flow in a closed circuit including the engine driven 30 fuel injection pump, the system further including a fuel return header arranged substantially above a fuel delivery header, and a device for collecting and delivering to the return header the fuel in excess of the requirements of the 35 pump, together with excess fuel released by the pump plunger on its delivery stroke; the present improvements objectively including provisions for removing from circulation, any air bubbles and vapor particles which might collect in the inverted pump chamber.

A still further object is attained in the provision, in an improved fuel system of the type described, of means for conveying excess fuel released by the fuel injection pump, to the fuel return conduit of the system, the means comprising a nozzle-like conduit section having a fuel-receiving port or opening therein, disposed in the path of fuel delivery to the pump and arranged adjacently opposite the pump inlet port, whereby 45 to receive the excess fuel released through the

inlet port, and to deliver such fuel to the return conduit of the system. The arrangement of the nozzle-like conduit relative to the pump inlet port, is such that the ejector and pressure wave action of the excess fuel released under considerable force by the injection pump, may be utilized to great advantage, in the maintenance of a continuous circulation of fuel in the supply system.

Further objects and advantages will appear 10 from the following description of parts and the accompanying drawings, in which:

Fig. 1 is a diagrammatic view of the assembled fuel supply system embodying the improvements of the present invention, the system being shown 15 as applied to an engine illustrated in sectional elevation; Fig. 2 is an enlarged fragmentary sectional view of an injection pump suitable for use in an engine of the type described, showing in connection therewith certain details of the present invention; Fig. 3 is a diagrammatic view of a fuel supply header and excess fuel return header system as applied to the fuel pumps of a multi-cylinder engine, and Fig. 4 is an enlarged fragmentary sectional view of an injection pump 20 suitable for use in an engine of the type described, showing in connection therewith certain details of the invention as modified with respect to the generally similar showing of Fig. 2.

For convenience in description and by way of 30 example of its application, the fuel system presently to be described is illustrated as applied to an opposed-piston type of two-cycle, solid-fuel injection internal combustion engine, the engine illustrated preferably being of Diesel type.

Referring now to the drawings, the numeral 10 designates, generally, an engine of Diesel type, having its pistons 11 and 12 arranged for operation in opposed relation, in a common cylinder 14. The engine is illustrated as being of single 40 cylinder, opposed piston type, but may be of either single or multi-cylinder type utilizing single or opposed pistons in each cylinder. The cylinder 14 is provided with suitably arranged scavenging ports 15 and exhaust ports 16. Air 45 under pressure for scavenging purposes, is delivered to the ports 15 through the conduit 18 and annular air chamber 19, while the exhaust gases and air are discharged through the ports 16 into the annular chamber 20, and through an 50 exhaust conduit 21 to the atmosphere. The lower piston 11, which controls the opening and closing of the exhaust ports 16, is operatively connected to a lower crankshaft 23 through the connecting rod 24, while the upper piston which 55

controls the scavenging ports 15, is connected to an upper crankshaft 26 through the rod 27. The two crankshafts are operatively connected by any suitable drive means (not shown) for maintaining synchronous operation thereof and for purposes of properly timing the movement of the pistons in uncovering the scavenging and exhaust ports. The drive connection between the crankshafts forms no part of the present invention, and hence is not illustrated, particularly as suitable drives for this purpose are well known in opposed-piston engines of the type described.

The engine is provided with fuel injection pumps 28 and 29, each thereof supplying fuel under pressure as through a conduit 30, to an injection nozzle structure 31. Each of the injection nozzles 31 is shown as disposed to deliver fuel to the combustion chamber in the cylinder through an opening 32 in the side wall thereof, this opening being located substantially midway between the ends of the cylinder. Since the injection pumps are identical in structure, only one thereof will be described in detail, the same reference characters applying equally to the corresponding parts of both pumps. However, it is to be understood that although the engine illustrated in Fig. 1 is of a type which utilizes a pair of injection pump and nozzle organizations for each cylinder, the fuel supply system presently to be described may be applied with equal facility to engines employing but a single injection pump for each cylinder.

Each of the injection pumps, shown as disposed in an inverted position in the present example, includes a pump casing 33, a stationary sleeve 34 within the casing and a pump plunger element 35 arranged for reciprocating movement in the sleeve. The plunger is operated by a cam element 36 on an engine driven cam shaft 37 (Fig. 1). The volume of fuel delivered by the pump to the injection nozzle is regulated in accordance with engine load requirements, as by the mechanism generally designated at 38 (Fig. 2), having an operative connection (not shown), with the plunger 35. The mechanism 38, which may be operated by the engine governor (not shown), and its connection to the pump plunger, is well known and forms no part of the present invention, hence no further description thereof need be given.

Referring to Fig. 2 which illustrates in cross section the lower or operating end of the pump, the casing 33 is provided with a fuel passage 39 through a wall portion thereof, the passage having a substantial sectional area, as shown. A fuel passage 40 of smaller sectional area than that of passage 39 is formed through a wall portion of the sleeve 34, the passage communicating on its outer end, through a slightly enlarged opening or port 41, with the casing passage 39, and on its inner end with the displacement chamber of the pump. The lower or operating end of the plunger is cut away as at 42 to provide an annular fuel pocket or chamber 43 between the plunger and the sleeve 34, the arrangement of the cut-away portion defining the pocket 43, being such that the pocket is in direct communication with the sleeve passage 40, only during the latter part of the full delivery stroke of the plunger. Briefly, during the suction stroke of the plunger, fuel from a suitable source will be drawn into the pump chamber, defined by the lower end portion of the sleeve 34, and into the pocket 43 through the port 41 and passage 40. During the first part of the pump delivery stroke such fuel

will be subjected to the loading of the plunger, and as the pocket 43 comes into communication with the passage 40, any excess fuel remaining in the chamber 43 will be ejected through the passage 40 with considerable velocity, as such excess fuel is compressed to a slight degree since confined at this time under high pressure.

A chambered fitting element 44 having chambers 46 and 47 therein, separated by a central wall or partition 48, is secured in any suitable manner (not shown) to the pump casing 33 with the chamber 46 in communication with the casing passage 39 through a connecting passage 49 in a wall portion of the fitting member. A nozzle-like tube or conduit section 50 having an outwardly flared end 51 defining a port 52, is arranged with the bell end 51 disposed within the passage 39, and with the port 52 in juxtaposition to and spaced from the port 41 of sleeve passage 40. The opposite end of the conduit 50 communicates with the chamber 47 in the member 44, the conduit extending through the passage 49, chamber 46 and the partition or wall 48, the conduit being by preference, supported by and secured to the wall 48. The chamber 46 in the fitting 44 is in communication with a fuel supply header 54 through the pipe connection 55, while the fitting chamber 47 is connected with a fuel return header 56 through the pipe connection 57.

The system for supplying fuel to the injection pumps will now be described. In the first instance, fuel is supplied to the header 54 of each pump from a suitable storage tank 58 which may be located either remotely from or relatively near the engine mounting. A feed pipe or conduit 59 extends from substantially the lower or bottom portion of the tank, to a fuel supply pump 60, whence the fuel is forced by the operation of the pump, through a conduit 61 having fuel filters 62 in circuit therewith, to a T-connection 63, and pipe or conduit 64 to a T-connection 65 from which extend branch conduits 66 and 67 to the supply headers 54 of the injection pumps 28 and 29, respectively. The return circuit for the fuel in excess of that utilized by the injection pumps, includes a conduit 68 connected to the return headers 56, as through the branches 69 and 69A, and leading to a completely enclosed, fuel-receiving tank 70 which may be and by preference is mounted upon the upper crank case 71 of the engine 10. A conduit 72 extends from the bottom portion of the tank 70 to a circulating pump 74, the pump being connected on its discharge end to the T-connection 63, as through a conduit 75. Thus a closed-circuit, fuel supply system is established, the circulating pump 74 drawing fuel from the tank 70 through the conduit 72 and delivering such fuel under pressure to the fuel supply headers 54 through the conduit 75, T-connection 63, conduit 64 and branches 66 and 67. A portion of the fuel so delivered is extracted by the injection pumps for consumption by the engine, and the excess thereof is returned to the tank 70 through the return headers 56 and conduit 68. The closed circulation system is constantly replenished with fresh, filtered fuel by the supply pump 60 in forcing fuel from the supply tank 58, through the filters 62 to the T-connection 63 and thence into the system. The self-priming feature characterizing the present system is a result of the elevated fuel tank 70, the continuous inflow of fresh, filtered fuel to the closed circulatory system, as effected by the fuel pump 60, and the pressure wave created by the ejection of excess fuel from

the injection pumps into the fuel return headers 56, the combined function of which, once the fuel flow is initiated, tends to maintain the flow in a manner which will be apparent from the description.

The pumps 60 and 74 may be separately driven by any suitable means (not shown), or they may be included as accessories or adjuncts of the engine organization 10 and hence driven thereby. With regard to the filters 62, it is desirable to connect at least two in the fuel supply line, to provide for an uninterrupted filtering of the fresh fuel delivered to the system, as such provision will permit one thereof to be in operation while the other is being cleaned or repaired.

As a means for removing or entrapping any air bubbles, emulsions, sludges and vapor particles collecting in the fuel circulation system, a vent valve 76 of suitable type such as a spring loaded, ball valve as illustrated in Fig. 1, is provided near the upper end of the fuel-receiving tank 70. The valve 76 is connected by a vent duct 78 with the upper portion of the main supply tank 58, whence the bubbles and vapor particles delivered thereto may pass to the atmosphere through the vent 79 in the tank 58. In the closed fuel supply system shown and described, all air bubbles, emulsions, sludges and vapor particles will ultimately collect in the tank 70, and since the tank 70 is mounted on the upper crankcase of the engine, the natural vibrations of the engine structure during engine operation, will be transmitted directly to the tank 70, hence the fuel in tank 70 will be agitated to an extent that all air bubbles and vapor particles accumulating therein will collect in the upper or top portion of the tank. When the volume of air bubbles, emulsions, sludges and vapor particles collecting in the upper portion of tank 70 is enough to create sufficient pressure to open the vent-valve 76, all foreign matter including the emulsions and sludges will be ejected into tank 58 and the air and vapor will be vented to atmosphere in the manner described. In order to prevent an undesirable degree of turbulence, there is provided in the tank 70, a baffle 77, located opposite the outlet of conduit 68.

In the operation of the improved fuel supply system herein described, the circulation pump 74 maintains a continuous movement of fuel from the tank 70, through the pump, to the fuel supply header 56 of each injection pump, whence the fuel flows to the fuel pump casing passage 39. A portion of the fuel so delivered will be utilized by each injection pump, in accordance with its governed demand, and the excess fuel remaining will flow from the passage 39 into and through the conduit 50 to the return header 56, whence it is returned to the tank 70. Also, any excess fuel delivered to the injection pump chamber will be released by the plunger during a portion of its operating stroke, and such fuel will be delivered to the return header 56 in a manner presently to be described. The supply pump 60 may operate continuously to replenish the closed circulating system with fresh, filtered fuel.

A particular feature of this invention is to be found in the provision of the nozzle-like tube 50 which is arranged with its fuel-receiving end 51 and inlet port 52 slightly spaced from and located oppositely and substantially in register with the inlet port 41 of the fuel passage 40 in the plunger-sleeve 34. The injection pumps are by preference mounted in an inverted position, and each thereof effects a pressure release of

excess fuel delivered to the pump chamber, which excess fuel is ejected as a result of the operation of the pump plunger, through the passage 40, across the space intervening the outer opening or port 41 of the passage 40 and the inlet end 51 of the tube 50, through the port 52 and into the tube 50, thence through the tube to the return header 56. With the pump in an inverted position, any air bubbles, emulsions, sludges and vapor particles will tend to collect in the top portion of the fuel space in the pump plunger. However, when the excess fuel under pressure in this space is ejected at a high velocity through the sleeve passage 40 and into the tube 50, the foreign matter, bubbles and vapor particles will be carried along with and entrained by such fuel, through the return header 56 and conduit 68 to the separator tank 70. Hence it will be readily observed that the ejector and pressure-wave action of the excess fuel so released, will not only remove foreign matter, air bubbles and vapor particles tending to become entrapped in the fuel pump, but will tend to assist the circulation of the fuel in the system. It will also appear that such action will tend to prevent a backflow of fuel from the return header to the pump during the suction stroke of the pump plunger. The momentum of the excess fuel released by the pump plunger on its delivery stroke, in carrying the excess fuel across the space between the passage 40 and the inlet end 51 of the tube 50, will tend to prevent, in addition, any part of such excess fuel from returning to the supply header.

The ejector action of the excess fuel is in certain circumstances, sufficient to maintain the circulation of fuel in the closed circuit system, without the use of a separate forced circulation device, such as the pump 74. For example, if the capacity of the injection pumps be substantially in excess of injection requirements, the volume of by-passed or excess liquid fuel is such as definitely to create and maintain a circulation through the system, without the necessity of a separate pump for this purpose. Under these conditions each injection pump serves the dual purpose of an injection, as well as a circulating agency, the ejector or aspirating action of the element 50 and associated parts serving more than adequately to maintain for the pump a plentiful supply of fresh clean liquid fuel at all times. In this case the pump 74 may be disconnected from its driving means, and a shunt or by-pass conduit connected between the conduits 72 and 75. Such a by-pass connection is shown at 80, Fig. 1. A two-way valve 81, which may be of conventional type, is provided at the juncture of the by-pass conduit 80 and conduit 72 for connecting the by-pass in the circulation system.

The fuel systems of the present invention may be utilized to supply multi-cylinder engines of a variety of types, as well as single-cylinder engines, such as that shown by way of example in Fig. 1. The provision for multi-cylinder engines is made through an arrangement exemplified in a diagrammatic manner in Fig. 3. In this figure, the reference characters 85, 85, 87 and 88 designate cylinders of a multi-cylinder engine, each of which is supplied with fuel by a pair of fuel pumps 89 and 90 preferably arranged on opposite sides of the cylinder in a plane which is substantially at a right angle to the longitudinal axis of the engine, i. e., the engine crankshaft axis. Thus a row of fuel pumps 75

89 are disposed on one side of the engine, and a similar row of pumps 90 on the opposite side of the engine.

Fuel oil from the supply system described in connection with the engine of Fig. 1, is delivered through the supply pipe or conduit 91 to the T-connection 92, from which branch conduits 93 and 94 extend to the first or right-hand pair of pumps 89 and 90 respectively. The described fuel connections correspond respectively to the connections 64, 65, 66 and 67 shown in Fig. 1. The fuel inlets of the pumps 89 are interconnected through a supply header 95, the header being supplied with fuel from the branch conduit 93. Similarly, the fuel inlets of the injection pumps 90 are interconnected through a supply header 96 which is supplied with fuel from the supply branch conduit 94. Fuel return headers 97 and 98, overlying respectively the branch supply lines 95 and 96, interconnect the outlets of the pumps 89 and 90 respectively, with both return headers connected to a common excess fuel return conduit 99 through branch conduits 100 and 101. The latter are connected respectively to the return headers 97 and 98. The connections 99, 100 and 101 of Fig. 3 correspond respectively in function, to the connections 68, 69 and 69A shown by Fig. 1.

For those engines utilizing but a single injection pump for each cylinder, the fuel supply system would appear substantially like that shown in Figs. 1 and 3, with the exception that the arrangement shown by Fig. 3 would include but a single row of injection pumps, say the row of pumps 89 supplied with fuel from the branch conduit 93 and supply header 95, the excess fuel of course being returned to the circulatory system through the return header 97 and return conduit 99.

40 Fig. 4 illustrates in sectional elevation the lower or operating end of an injection pump, the view being similar to that of Fig. 2 but showing certain modified features in the structure thereof. The pump comprises a casing 105 having an externally bossed portion 106 on one side thereof, the boss providing a plane surface 107 to which is secured in any suitable manner (not shown) a fitting member 108. A sleeve 109, serving as a guide for the pump plunger 110, is secured within the casing 105 and is provided with a fuel passage 111 through a wall portion thereof. A fuel passage 112 extends laterally through a portion of the boss 106, and the sleeve 109 is so disposed within the pump casing as to effect a radial alignment of the sleeve passage 111 with the passage 112. A second fuel passage 114 is formed through the boss 106, this passage by preference being sloped upwardly and inwardly of the casing wall. The inner end of this last passage is in communication with the passages 111 and 112 through a somewhat arcuately slotted passage or recess 115 formed in a peripheral portion of the sleeve 109, in the manner illustrated in Fig. 4.

The fitting member 108 carries a fuel supply header 116 and a fuel return header 117, the headers being mounted in suitable seat portions 118 formed on the member, and secured thereto as by welding at 119. The supply header 116 communicates with the pump passage 114 through a connecting passage 120 formed in the fitting member 108. Similarly, the return header is in communication with the pump passage 112 through a connecting passage 121 in the fitting member.

75 The closed circulatory fuel supply system de-

scribed in connection with the engine of Fig. 1, supplies fuel to the header 116, from which the fuel flows under the pressure existing in the system, through the passages 120, 114, 115, 112 and 121 to the return header 117. The fuel received by the header 117 is returned to the circulating system in the manner heretofore described. During operation of the engine, and therefore of the fuel injection pump, the pump will draw fuel from the described flow of fuel from supply header 116 to the return header 117, the fuel flowing through passage 111 into the pump displacement space or chamber. Such fuel as is unused by the pump upon each delivery stroke, will be ejected through passage 111 into the passage 112. The momentum of the excess fuel thus ejected is normally sufficient of itself to prevent a backflow of the excess fuel into the supply header 116. In brief, the operation of the modified pump organization of Fig. 4 is similar to that described for the pump embodiment of Fig. 2.

Throughout the drawings, suitable arrows are provided to indicate the direction of fuel flow in the fuel supply system.

The presently described embodiment and improved features of this invention provides a fuel supply system which is fully automatic in its operation and is self-priming and self-venting. It is to be understood, of course, that the invention is not limited to the particular system and improved features thereof described and illustrated, but that alterations or modifications may be made in the parts, combinations and arrangements thereof without departing from the spirit and full intended scope of the invention, as defined by the appended claims.

I claim:

1. In a liquid-fuel injection system for internal combustion engines, an injection pump provided with a fuel inlet port, means forming a supply chamber communicating with said pump inlet port, a supply connection to the chamber, an outlet connection from the chamber, a tubular conduit element in said chamber, provided for conducting fuel from the supply connection to the outlet connection through said chamber independently of the pump said tubular conduit having its inlet end spaced from and in line with said pump inlet port, and conduit means connecting the supply and outlet in a continuous circulating system.

2. In a liquid-fuel injection system for internal combustion engines, an injection pump of a type having a displacement capacity in excess of injection requirements, the pump including a pump chamber and a port communicating therewith, said port providing both a fuel inlet and an excess fuel outlet for said pump chamber, and a system of conduits arranged, independently of the pump structure, for continuously circulating a supply of fuel to and from the pump, said system including a fuel reservoir having a continuous connection with the pump through said pump port, an inlet connection and an outlet connection, each associated with the reservoir, conduit means connecting the outlet connection to the inlet connection, and means constituted by elements of said system and including a short conduit section of reduced diameter, disposed within the reservoir adjacent the pump and in the line of flow of excess fuel from said pump port, and tending to create a circulation of liquid fuel through the system.

3. In a liquid-fuel injection system for an internal combustion engine, an injection pump, a

fuel supply reservoir adjacent said pump, and in constant communication therewith, the reservoir being provided with an inlet port and an outlet port, each in constant communication with the other and with the pump, and a system of conduits and means associated therewith, arranged continuously to circulate a supply of fuel from the said outlet port to the said inlet port of the reservoir, the conduit system including a supply tank, and means in the conduit system tending to entrap and remove foreign matter, air and vapor particles from the system, said means including a fuel and vapor separator located on the engine and above said fuel supply reservoir and the supply tank.

4. In a liquid-fuel injection system for an internal combustion engine of multi-cylinder type, a system of fuel delivery and return conduits arranged in closed circuit relation for the continuous circulation of liquid fuel, means for supplying fuel to said system, including a fuel supply reservoir in the system, an injection pump for each cylinder of a type having a displacement capacity in excess of injection requirements, said pumps being connected to said system in parallel, between said fuel delivery and return conduits, and means located in the system adjacent each pump, utilizing the expulsion of excess fuel from the pump, concurrently to promote a positive and continuous circulation of liquid in the system, and to induce a flow of fresh fuel from the system to the pump.

5. In combination with an injection pump of a type having an excess-fuel discharge port, a pump fitting formed of a pair of mating elements, each of said elements being provided with connecting bores forming a pair of passages through the fitting, outer portions of the fitting being formed to receive a fuel supply conduit and a fuel return conduit located for connection respectively with said passages, a portion of the pump structure being formed to provide an arcuate recess of appreciable extent in a direction axially of the pump and adjacent the fitting, and the fitting being formed so that the passages therethrough open into said recess, the recess being in communication at one end with the excess-fuel discharge port of the pump, and a portion of the passage through the fitting to the return conduit, being in register and in substantial alignment with said port.

6. In an injection pump assembly for engines of the type described, an injection pump of a type having a displacement capacity in excess of injection requirements, said pump including a pump cylinder having a passage through a wall

portion thereof, a sleeve in said cylinder having a fuel port therein in communication with said passage, a pump plunger operable in said sleeve, a hollow member provided with separate chambers therein, one of said chambers being in communication with said cylinder passage, a fuel supply header in communication with said last-mentioned chamber, a fuel return header in communication with the other of said chambers, and a conduit extending from said other chamber through the first said chamber and into said cylinder passage, said conduit having an open end spaced from but aligned with the fuel port in said sleeve and adapted to receive excess fuel released by said plunger on its delivery stroke.

7. In an injection apparatus for an engine of liquid-fuel injection type, an injection pump, a fuel feeding system including a fuel supply tank communicating with the pump, a device connected into said system for separating foreign matter from the fuel therein, said device comprising a substantially closed container located above said injection pump and mounted on the engine so as to be subject to engine vibration to effect an agitation of the container, the container having a supply connection to its upper portion, and an outlet connection from its lower portion, means within the container tending normally to maintain a body of liquid therein, and a vapor space above the liquid, an outlet connection from said vapor space, and a vent duct having its inlet at the last said connection and its outlet in the upper portion of said supply tank.

8. In a liquid fuel injection apparatus for internal combustion engines, an injection pump, a fuel supply system including a supply tank communicating with said pump, a device in the fuel system tending to entrap and separate from the fuel therein, foreign matter, air and vapor particles, said device comprising a container located above said injection pump and mounted on a portion of the engine subjected to engine vibration to effect an agitation of the container, the container being supplied from said system by connection to an upper portion thereof, and provided with a liquid discharge port in a lower container portion, the container being so related to the system as normally to maintain in its upper portion a space above a body of liquid therein, a vent duct extending from said space into said supply tank, and a check valve in the vent-duct adapted to effect a permanent separation of foreign matter, air and vapor particles from said container space.

FREDERICK RITZ. 55
